UNITED STATES PATENT OFFICE.

JOSEPH BARRAJA-FRAUENFELDER, OF BRIDGEPORT, CONNECTICUT, ASSIGNOR TO THE LAKE TORPEDO BOAT COMPANY OF MAINE, OF BRIDGEPORT, CONNECTICUT, A CORPORATION OF MAINE.

MOTIVE POWER FOR SUBMARINE BOATS.

1,190,211.

Specification of Letters Patent.

Patented July 4, 1916.

Application filed April 29, 1915. Serial No. 24,792.

To all whom it may concern:

Be it known that I, JOSEPH BARRAJA-FRAUENFELDER, a citizen of the United States, residing at Bridgeport, in the county 5 of Fairfield and State of Connecticut, have invented certain new and useful Improvements in Motive Power for Submarine Boats, of which the following is a specification.

10. The invention relates to an improvement in submarine or submersible torpedo boats using steam as a motive power when operating upon the surface of the water.

Heretofore, the use of steam power in submarine torpedo boats has not been found practicable, owing to the intense heat emitted from the boilers and engines, and as no provision has heretofore been made for cooling the boilers and the surrounding space there- 20 of, the heat trapped in the boat or in the boiler compartment when the hatches and ventilators are closed prior to submersion, subjects the crew to extreme discomfort and danger, since it is known that the tempera- 25 ture frequently rises to as high as 130° F.

The object of my invention is to obviate this difficulty and to provide an arrangement for rapidly condensing the steam remaining in the boilers after the fire in the fire-boxes 30 of the boilers has been drawn or extin- guished, and for withdrawing and cooling the hot water remaining in the boilers, means being provided for circulating the boiler water through the condenser so that the latter 35 will serve as a cooler for reducing the temperature of the boiler water, and means also being provided for supplying the boiler with fresh water when steam is being generated for use in the engines.

40. The invention consists in providing a condenser into which the steam and the hot water from the boilers and engines are designed to be admitted after the fires of the boilers have been extinguished, said condenser being 45 connected with the external or sea water and having a pump connected thereto for causing a circulation of the external or sea-water therethrough, whereby to condense the steam and to cool the hot water as it passes through 50 the condenser.

The invention further consists in an arrangement for passing the cooled water back into the boiler to thus rapidly cool the latter so that but comparatively little heat is radi-

ated from the boiler after the fire has been 55 extinguished thus permitting the boat to be submerged in as short a time and without discomfort or danger to the crew as is now done with boats using internal combustion or heavy oil engines, said means also serving 60 to supply the boiler with water as it is consumed therein.

The invention further consists in certain details of construction, combination and arrangement of parts as will be hereinafter 65 fully described and then pointed out in the claims.

In the accompanying drawings, illustrating the invention, in the several figures of which like parts are similarly designated, 70 Figure 1 is a diagrammatic vertical longitudinal section of the amidships and after section of a submarine boat embodying my improvements. Fig. 2 is a diagrammatic view illustrating my invention, the turbines 75 or motors being omitted. Fig. 3 is a plan view illustrating the arrangement of the turbine engines; the condenser, and the air pump.

1 designates the hull of a submarine or 80 submersible boat, and 1' the superstructure, the amidships section and after end only being shown. Within the main hull is built a boiler-room 2, preferably of the construction shown and described in United States Let- 85 ters Patent No. 1,134,940, granted to me April 6, 1915, and assigned to The Lake Torpedo Boat Company of Maine. As the special construction of boiler-room, how- 90 ever, forms no part of the present invention, I have not thought it necessary to illustrate or describe this feature in detail, and, furthermore, for the purpose of illustration, I show the boiler-room provided with only one boiler (3), however, it will be understood 95 that two or more boilers may be used according to the power and speed of the boat.

4 designates turbine engines of any ap- 100 proved type suitably geared to the propeller shafts 5 which extend through the boat in the usual manner, and provided at their outer ends with propellers 6. As shown diagrammatically in Fig. 3, the propeller shafts will have suitable clutches 5' inter- 105 posed therein by which the direction of rotation of the propeller shafts and their pro- pellers may be governed. The turbines are supplied with steam through pipes 7 suit-

ably connected with the steam dome of the boiler 3.

The turbines are mounted upon a horizontal platform 4 arranged within the boat, 5 and below the said platform is arranged a condenser 8, to which is connected a pipe 9 extending from a pump 10 having a pipe 11 connected to the suction thereof, and which extends from the steam dome 3' of the 10 boiler, the said pipe 11 being extended down into the said steam dome below the level of the water for the purpose as will hereinafter appear. The pump 10 is driven by a suitable electric motor 12, as shown diagrammatically in Fig. 2. The condenser 8 may 15 be of any suitable design having water pipes (not shown) therein, which are connected at their opposite ends to water spaces 13, to one of which spaces is connected the outlet 20 of a circulating pump 14 having its suction or intake connected with the sea. The water space at the opposite end of the condenser is connected by a pipe 15 which is designed to discharge into the sea, and may be, by preference, in open communication therewith. 25 The circulating pump 14 is driven by a suitable electric motor 14', which, it will be understood, when set in motion, will drive the pump to draw water from the sea and force 30 it through the condenser and then out through the pipe 15, thus causing a constant circulation through the condenser to keep it cool and thus cool the hot water from the boiler as it is admitted to the condenser.

35 As the water from the boiler is cooled in the condenser it is withdrawn therefrom through a pipe 16 having one end connected with the bottom of the condenser, and its opposite end connected to a combined dry and 40 wet air pump 17 of marine or other suitable type, and from the outlet of the pump extends a pipe 17' which is connected to a suitable feed and filtering tank 18, which may be built within the main hull of the boat 45 in a similar manner as the fuel or fresh water tanks of the present and accepted types of submarine boats, or which may be a separate, portable tank of suitable design. To the lower end of the tank 18 is connected 50 an outlet pipe 19 extending from a suitable rotary pump 20 from the outlet of which extends a pipe 21 having its opposite end connected to the water-jacket of the boiler 3. Valves 24 are arranged in the several pipes 55 to control the passage of water and steam therethrough. The pumps 17 and 20 are driven by suitable electric motors 25 and 26, respectively.

Further understanding of the invention 60 will be best had from the following general description of the operation thereof.

After the smoke stack of the boiler 3 has been closed, and the fire in the boiler has been extinguished, the valve 24 in the pipe 65 11 is opened, and the pumps 10, 14, 17 and

20 are then set in motion, the valve 24 in the pipe 7 being in the meantime closed so as to cut off the admission of any steam remaining in the boiler to the turbines. As the pumps 10, 14, 17 and 20 are set in motion, the pump 10 will draw the hot water from the top of the boiler and inject it into the condenser 8 in which it is rapidly cooled, the pump 14, it being understood, will set up a circulation of the external or sea-water through the said condenser, thus keeping the latter cool. As the water from the boiler passes through the condenser 8, it is drawn therefrom through the combined dry and wet air pump 17, and forced into the combined feed and filter tank 18 from which, after being filtered, it is withdrawn and forced into the water-jacket of the boiler by means of the pump 20, thus completing the cycle. It will be understood that as the hot water is withdrawn from the upper end of the boiler, and the cooled water is admitted into the lower end of the water-jacket, the steam remaining in the steam dome will naturally be condensed.

In practice the condenser 8 will be provided in its upper end with a perforated pipe 8' into which the hot water is injected, which pipe serves to admit the hot water in small streams into the condenser throughout the length thereof, thus distributing the water throughout the condenser so as to more rapidly cool the same.

The expanded steam from the turbines 4 is conducted into the condenser 8 through ducts 7' and the water reduced from the steam and also the cooled water from the boiler will be pumped into the combined supply and filter tank 18 to be used again in the boiler. It will thus be seen that the condenser 8 serves the double purpose of a condenser and a water cooler.

It will be understood that if the level of the water of the feed and filtering tank 18 is located above the level of the water in the boiler, the pump 20 may be dispensed with and the water thus permitted to run by gravity from the said tank 18 to the said boiler.

What I claim is:—

1. In a submarine boat, a steam generating plant, a motor connected with said plant, and a condenser independently connected with said steam generating plant and with the exhaust of said motor, a valve for closing communication between said generating plant and said condenser, and means interposed between said generating plant and condenser for drawing the steam and hot water from said generating plant into said condenser when said valve is opened, to rapidly reduce the temperature of the generating plant, said condenser thereby serving as a cooler for the steam and hot water drawn from the generating plant.

plant and as a condenser for condensing the exhaust steam from the motor, substantially as and for the purpose specified.

2. In a submarine boat, a steam generating plant, a turbine motor piped to said steam generating plant, a propeller geared to said motor, a condenser independently piped to said steam generating plant, means for drawing the water from the generating plant into said condenser, a pump for forcing external water through said condenser, and means for supplying said steam generating plant with fresh water.

3. In a submarine boat, a steam generating plant located therein, turbine motors piped to said steam generating plant and operatively geared with the propellers of the boat, a condenser independently connected to said steam generating plant and to said turbine motors, means for drawing the water from the generating plant into said condenser, means for causing a circulation of external water through said condenser for the purpose specified, a source of fresh water supply piped to said steam generating plant, and a pump for forcing water into said steam generating plant.

4. In a submarine boat, a steam generating plant located therein, turbine motors piped to said steam generating plant and operatively connected with the propellers of the boat, a condenser independently piped to said steam generating plant, means for

35 withdrawing hot water from said steam generating plant and for spraying it into said condenser, means for forcing external cooling water through said condenser, said condenser serving as a cooler for the hot water from the generating plant, means for withdrawing the cooled water from said condenser, and means for passing the cool water drawn from the condenser back to the said steam generating plant.

5. In combination with a submarine boat having a steam generating plant arranged therein, a turbine motor piped to said steam generating plant, and a propeller geared to said turbine motor, of a combined condenser and cooler independently piped to said steam generating plant and to said motor, means 45 for circulating external water through said condenser, means for withdrawing the hot water from said steam generating plant and forcing it into said condenser and cooler, a combined feed and filtering tank arranged 50 within the boat, means for conducting the cooled water from said condenser and cooler and forcing it into said tank, and means for conducting the cooled water from said tank back to said steam generating plant.

In testimony whereof I have hereunto set my hand this 26th day of April, A. D. 1915.

JOSEPH BARRAJA-FRAUNFELDER.
